UNITED STATES PATENT OFFICE.

LEON PIERCE, OF NEW YORK, N. Y.

POWER-HAMMER.

1,158,839.

Specification of Letters Patent. Patented Nov. 2, 1915.

Application filed August 11, 1915. Serial No. 44,879.

To all whom it may concern:

Be it known that I, LEON PIERCE, a citizen of the United States, and a resident of New York city, county and State of New York, have invented certain new and useful Improvements in Power-Hammers, of which the following is a specification.

This invention relates to power hammers and the objects of the invention are to construct a power hammer for driving piles or the like that is nearly noiseless in operation.

To the accomplishment of the above objects and to such others as may hereinafter appear the invention comprises an inclosed hammer arranged to be mounted upon the upper end of a pile to be driven and provided with means for confining water or the like adjacent to the top of the pile through the medium of which the striking head of the hammer operates to drive the pile, thereby deadening the sound incident to the driving of piles when the striking head comes into direct contact with the pile or anvil plate.

I will now proceed to describe my invention with reference to the accompanying drawings, and will then point out the novel features in claims.

In said drawings: Figure 1 is a side view partly in section of a hammer made in accordance with the invention. Fig. 2 is a perspective view of the hammer shown in Fig. 1, with parts broken away. Fig. 3 is a transverse sectional view taken on the line 3—3 of Fig. 1. Fig. 4 is a detail sectional view of the hammer head and dolly plate in striking position.

In the drawings, 1 designates the hammer frame which is provided in the present instance, on its side edges with vertical ribs 2 which form channels or guideways for the reception of the guide bars of the usual tower or other support in which this type of hammer is usually mounted.

The upper end of the frame 1 is open and suitably supports a heavy top or cap 3 securely bolted to the top of the frame. Formed integral with the cap 3 is a central depending post 4 which serves as a rigid immovable piston rod. To the lower end of this rod is secured a piston 5. Mounted on this piston and piston rod is a vertically reciprocating cylinder 6 having a head 7 screwed thereon and provided with a stuffing box 8. The lower end of the cylinder is formed with a suitable hammer head 9.

The cylinder is formed at its sides with vertical grooves 10 which fit corresponding guides 11 in the hammer frame, said guides preventing any rotation of the cylinder in the frame.

The top or cap 3 is provided, in the present instance, with a cylindrical valve casing 12 having a cylindrical valve 13 connected to a steam inlet pipe 14. This valve 13 is arranged to admit steam alternately to two longitudinally extending passages 15 and 16 in the rigid piston rod 4. The passage 15 extends from the valve casing through the piston rod, opening into the cylinder below the piston, while the passage 16 extends from the valve casing through the piston rod, opening into the cylinder above the piston, as clearly shown in the drawings.

The valve 13 is operated through the medium of a valve stem 17, shown in dotted lines, which is pivotally connected to a link 18, the opposite ends of which are pivotally connected to the upper ends of valve operating levers 19 and 20, said levers being pivoted in the main frame at 21 and 22. Formed on opposite sides of the cylinder are beveled cams 23 and 24, the cam 24 being formed near the upper end of the cylinder and having a suitable cam surface inclining inwardly and downwardly, while the cam 23 is near the lower end of the cylinder and is formed with a cam surface which inclines inwardly and upwardly. The cam 24 is adapted to engage the roller 25 of the valve operating lever 20 as the cylinder completes its downward movement; and the cam 23 is adapted to engage the roller 26 of the valve operating lever 19 as the cylinder completes its upward movement.

It is manifest, therefore, that as the cylinder completes its downward movement, the position shown in Fig. 1, the valve 13 will be operated to admit steam to the passage 16 to raise the cylinder, and when the cylinder completes its upward movement the valve 13 will be again operated so as to admit steam to the passage 15 to force the cylinder down. The exhaust steam from either side of the piston passing out through suitable ports 27 and 28 into the exhaust pipe 29 which extends through the cap 3 down into the interior of the hammer frame, the purpose of which will be explained later.

The hammer head 9 on the end of the cylinder is adapted to fit a hammer hole 30 in the hammer frame, the lower end of the hole

30 being closed by means of a dolly plate or anvil plate 31 held in a suitably enlarged recess 32 in the frame, as shown in Fig. 4. The dolly plate 31 is inserted into position 5 through a suitable side opening in the frame which is closed by means of a plate 33, shown in Fig. 2.

The lower end of the hammer frame is recessed below the dolly plate recess as shown 10 at 34, to receive the upper end of a pile or anvil pipe 35 which bears directly against the bottom of the dolly plate 31, the weight of the hammer keeping the parts in the position shown in Fig. 4.

15 The bottom of the hammer frame is closed by means of a ring plate 36 to which is secured a cylindrical band 37 by means of an angle band 38. To the inner surface of the band 37 is secured a cylindrical strip of leather or rubber 39 the top edge of which engages the outer surfaces of the anvil pipe 35. The sides of the hammer frame near the bottom are recessed and these recesses are covered by means of suitable plates 40.

25 The open side portions of the frame that inclose the cylinder 6 are closed by means of suitable covers 41, preferably made hollow and provided with corrugated pieces of metal 42 to deaden the sound made by the 30 hammer.

From the above description it will be seen that the exhaust steam as it leaves the exhaust ports 27 and 28 passes out through the exhaust pipe 29 into the inclosed casing surrounding the hammer which effectively muffles the sound of the exhaust steam, which is allowed to pass out through the pipe 42' or through the openings 43 through 35 which the valve levers 19 and 20 pass.

40 The exhaust steam as it condenses in the inclosed casing runs down into the hammer hole 30 of the frame and collects upon the top of the dolly plate 31 so as to deaden the sound of the blow as the hammer head 9 45 strikes the dolly plate, the excess water being retained below the dolly plate by means of the cylindrical strip 39 before described.

In Fig. 4 is shown the position of the hammer head 9 in relation to the layer of water 50 and the dolly plate as the hammer head strikes, after which the hammer frame rises slightly as shown in Fig. 1, due to the force of the blow, the frame of the hammer and the layer of water on the dolly plate assuming the position shown in Fig. 4 before the next blow is struck.

A tap 44 is provided in the frame to prevent the water rising too high in the hole 30.

55 From the above description it will be seen that means are provided for muffling the exhaust steam used in driving the hammer by discharging the same on the inside of the frame surrounding the operating parts of the hammer which have been enclosed for this purpose. The means pro-

vided for muffling the exhaust do not take up any additional room so as to enlarge the space occupied by the hammer or impair its efficiency in any manner.

From the above description it will also be 70 seen that as the exhaust steam condenses it provides a continuous supply of water which is confined in the hammer hole on top of the dolly plate so as to deaden the sound of the hammer, the excess water being confined below the dolly plate as before described. 75

An ordinary steam hammer used in driving piles makes a great deal of noise and where it is necessary to drive piles next to 80 large buildings, the tenants are put to a great deal of inconvenience and annoyance that often necessitate their vacating the buildings in the near vicinity of the hammer. 85

A steam hammer made as above described effectively muffles the exhaust steam and the noise made by the hammer in pounding is also effectively silenced.

In the present instance the anvil pipe 35 90 is mounted upon a driving head 50 which is mounted on top of the pipe pile 51. The driving head 50 has been made the subject matter of a co-pending application no claim having been made in this application. 95

While the invention has been described with particular reference to the details of construction the same is not to be considered as limited thereto, as many changes can be made and still fall within the scope of the 100 invention set forth in the following claims.

I claim—

1. A power hammer comprising in combination a hammer frame, a reciprocating hammer mounted in said frame, steam operated means for reciprocating said hammer, means for inclosing said hammer in said frame, and means for discharging the exhaust steam used in operating the hammer on the inside of the hammer frame to 105 muffle the sound of the exhaust.

2. A power hammer comprising in combination a hammer frame having a hammer hole, a reciprocating hammer mounted in said frame and arranged to engage said hammer hole, a dolly plate supported in said frame below said hammer hole, said dolly plate being arranged to retain water in said hammer hole for deadening the sound of the hammer against said dolly 115 plate.

3. A power hammer comprising in combination a hammer frame having a hammer hole, a reciprocating hammer mounted in said frame and arranged to engage said 125 hammer hole, a dolly plate supported in said frame below said hammer hole, said dolly plate being arranged to retain water in said hammer hole for deadening the sound of the hammer against said dolly 120 plate.

130

plate, and means for supplying water to said hammer hole and means for retaining said water at a certain level in said hole.

4. A power hammer comprising in combination a hammer frame having a hammer hole, a reciprocating hammer mounted in said frame and arranged to engage said hammer hole, a dolly plate supported in said frame and arranged to close the bottom of said hammer hole, steam operated means for reciprocating said hammer, means for inclosing said hammer in said frame, and means for discharging the exhaust steam

used in operating the hammer on the inside of the hammer frame to muffle the sound of the exhaust and confine the condensed water in said hammer hole above said dolly plate to deaden the sound of the hammer.

In testimony whereof I have signed this specification in the presence of two subscribing witnesses.

LEON PIERCE.
